Des. 184,891
Patented Apr. 14, 1959

184,891

DRESSED DOLL

Jean Layton Rapp, Philadelphia, Pa., assignor to The R. T. French Company, Rochester, N.Y., a corporation of Delaware

Application July 16, 1958, Serial No. 51,810

Term of patent 14 years

(Cl. D34—4)

Des. 184,891

Fig. 2

Fig. 1 is a front view of a dressed doll embodying my new design;

Fig. 2 is a side view of this doll; and

Fig. 3 is a back view thereof.

I claim:

The ornamental design for a dressed doll, substantially as shown.
